TYPE-WRITING MACHINE.

No. 839,492.

Specification of Letters Patent.

Patented Dec. 25, 1906.

Application filed December 30, 1904. Serial No. 238,987.

To all whom it may concern:

* Be it known that I, ANDREW T. MACCOY, of Dover, in the county of Norfolk and State of Massachusetts, have invented certain new and useful Improvements in Type-Writing Machines, of which the following is a specification.

This invention has relation to type-writing machines, and more particularly to those machines which are electrically operated, such as "page-printing stock-tickers," so called, although many features of the invention are capable of embodiment in type-writing machines of other types.

15 The embodiment of the invention illustrated on the drawings consists of a type-wheel which is rotated and selectively positioned by a key-controlled electric motor. The type-wheel and the motor are mounted 20 to oscillate about a vertical axis to feed the type-wheel across the concave face of a platen, and an electromagnetic mechanism is employed for imparting the feeding movement thereto. A spring is employed for returning them; but it is not rendered active, except when they reach a predetermined 25 point in their feed and when one of the shift-keys is manipulated. The same electromagnetic is used for imparting an impression 30 stroke to the type-wheel radially of the axis of oscillation of the motor and the type-wheel as is employed for the feeding operation. Automatic paper-feeding mechanism is employed, and it is actuated by the said 35 electromagnet when the feeding mechanism has fed the type-wheel to the end of a line. The electric motor and the said electric magnet derive their current from the same source which supplies, first, an alternating 40 current, which energizes the motor to rotate the type-wheel, but does not affect the electromagnet, and then a direct current to hold the type-wheel against further rotation and to energize the magnet and cause it to perform its functions.

45 On the type-wheel there is a line of characters and blank spaces, the alternate characters and spaces having a potential printing relation to the platen. By mechanism 50 controlled by a shift-key the type-wheel is rotatively shifted one space to either of two positions relatively to the motor-shaft to which it is geared to bring the former non-potential characters and spaces into poten-

tial printing relation to the platen and to remove the first-mentioned characters and spaces to a non-potential relation, so that each character-key on the keyboard may be used for causing the printing of either of two characters by the type-wheel. An electromagnetic mechanism connected in multiple with the electromagnet hereinbefore referred to is automatically cut into circuit when one of the shift-keys is manipulated to prevent the feeding of the type-wheel on the shifting 65 of the type-wheel, for otherwise the feeding would occur, since the shifting is effected when the type-wheel has been positioned and has had the impression-stroke imparted to it by the said electromagnet.

70 Either of the shift-keys operates to render the carriage-returning means active by partially closing a branch circuit to an electromagnetic, which lifts a feeding and a retaining pawl from a ratchet on the type-wheel carriage, the complete closing of said branch circuit being effected by a switch, which is automatically operated when the type-wheel has reached the end of a line.

75 On the accompanying drawings, Figure 1 represents in side elevation a machine embodying the invention. In this figure the platen for the paper and the paper are illustrated in vertical section. Fig. 2 represents a plan view of the same. Fig. 3 represents a 80 front elevation. Fig. 4 represents a rear elevation, partially in section, on the line 4-4 of Fig. 1. Fig. 5 represents a machine in side elevation with the carriage swung to the extreme of its movement to the right across the 85 sheet. In this view the paper-guiding and the printing devices are not shown. Fig. 6 illustrates a portion of the machine in detail and shows the frame in which the carriage is journaled. This figure shows in detail the 90 mechanism for effecting the feeding of the paper. Fig. 7 represents, partially in section, the type-wheel and the means for effecting a movement of said type-wheel relatively to its 95 supporting means. Fig. 8 is a section on the line 8-8 of Fig. 7. In this figure the means for shifting the type-wheel to its other position occupy the preparatory position for the purpose. Fig. 9 illustrates the same parts 100 after being shifted. Fig. 10 illustrates the same parts in position preparatory to being shifted back to the former position. Fig. 11 shows the shifting means after being shifted 105

back to the former position. Fig. 12 represents the motor for the type-wheel detached. Fig. 13 represents an end elevation of the motor. In this figure the armature occupies 5 the position determined by a current of a given polarity. Fig. 14 represents a section on the line 14 14 of Fig. 13. Fig. 15 represents a section on the line 15 15 of Fig. 12. Fig. 16 represents an end view of the motor 10 which, taken in conjunction with Fig. 13, illustrates the armature in the position determined by a current of opposite polarity. Fig. 17 is a diagrammatic view illustrating the electrical circuits and the electromagnetic mechanisms for effecting the operation of the various parts of the machine. Fig. 18 is a diagram representing a pole-changing device or transmitter, a keyboard, a "sunflower," and an electromagnetic clutch or 15 stop-motion for determining the polarity of the current which passes through the machine and which causes the operation of the electromagnetic mechanisms of the machine.

20 I desire to have it understood at the outset that the machine shown in the drawings thus briefly described is one embodiment of the many of which the invention is capable, that the invention is not limited to the details of 25 construction of the machine or to any particular form of transmitting or controlling devices, and that the phraseology which I employ in the specification and claims is for the purpose of description and not of limitation.

30 The devices by which the machine may be controlled by the operator include a keyboard and a sunflower and a transmitter or pole-changer, which are rotated in unison.

35 The type-wheel of the machine is continuously rotated with a step-by-step movement 40 by a novel motor which I have devised, the motor being energized by an alternating current, in which the changes of polarity are too frequent to cause the mechanical operation 45 of the various mechanisms by electromagnets which are in series connection therewith, but are sufficiently infrequent to effect one step in the rotation of the type-wheel for each alternation. The current is supplied to the 50 motor through a transmitter or pole-changer, which is automatically stopped upon the depression of a key to cause the transmission of a direct current to the motor, whereupon the motor and the type-wheel are stopped in 55 their rotation with a type or space presented to the paper corresponding to said key, and the electromagnetic mechanisms are operated to feed or return the carriage, impel the type-wheel toward the paper, or feed the paper, as 60 the case may be. The type-wheel is so geared to the motor and the motor is so constructed that the rotation of the type-wheel is substantially synchronous with the rotation of the pole-changer or transmitter and 65 of the moving contact of the sunflower. The

keys on the keyboard are respectively electrically connected with the stationary contacts on the sunflower and are all electrically connected with an electromagnet stop mechanism, so that when a key is depressed a circuit through the corresponding stationary contact on the sunflower will be closed by the movable contact thereon to actuate the stop mechanism to stop the pole-changer, and therefore the type-wheel, in its rotation and 70 effect the operation of the various mechanisms of the machine.

Referring to Fig. 18, B indicates a keyboard, having a plurality of keys, (indicated at $b b' b^2 b^3 b^4$, &c.) This keyboard is located 75 at a main or central station where the transmitter is placed. The key b is the spacing-key and the keys $b' b^2$ are what are termed "shift-keys." The remainder of the keys are character-keys. In the sending mechanism 80 I propose to reduce the number of the character-keys, so that one key may be used for each of two different characters—as, for instance, one key may be used for the letter "a" and numeral "1," another for "b" and 85 "2," and a third for "c" and "3," &c. Each of these keys $b b' b^2 b^3$, &c., is connected by a separate branch circuit $c c$ with the stationary contacts d of the sunflower D. The rotary arm d' of the sunflower is on a yieldingly-driven shaft E, said shaft having thereon a stop-wheel F and the pole-changer or 90 transmitter G. e indicates a circuit having a source of electrical energy e' included therein, said circuit including the arm d' and serving as the return-wire for the branch circuits $c c$. In the circuit e is placed an electromagnet e^2 , the armature e^3 of which is mounted 95 upon a movable stop member e^4 , arranged in operative relation to the stop-wheel f and normally held away therefrom by a spring e^5 . The stop-wheel F is provided with a plurality of teeth f equal in number to the keys of the keyboard, which, as previously stated, are also equal in number to the contacts d on 100 the sunflower. The pole-changer or transmitter G has upon its periphery a plurality of contacts g' , arranged in staggered relation with their ends overlapping or projecting past each other. The shaft E is yieldingly 105 driven by any suitable means. (Not illustrated.) Bearing upon the periphery of the pole-changer are two brushes $g^2 g^3$, which are connected in two different circuits $g^4 g^5$ of opposite polarity. The two circuits $g^4 g^5$ have 110 separate sources of electrical energy, (indicated at $g^6 g^8$). The brushes $g^2 g^3$ are engaged alternately by the contacts g' as the pole-changer rotates. Arranged between 115 said brushes is a third brush g^7 , which is successively engaged by all of the contacts g' , this brush g^7 being connected with the main working circuit, which is indicated at H, the conductor of which is connected to a binding-post 120 on the base of the machine, but 125 130

insulated therefrom. The machine has another binding-post 112, from which the circuit H is grounded, there being a ground connection between the sources of electrical energy g^6 g^8 , as illustrated in Fig. 18. The type-wheel, which is indicated as a whole at 27, has upon its periphery subdivisions which are double in number to the keys on the keyboard. Of these divisions six are blank, as shown in Fig. 18, the remainder bearing the usual types which are used in type-writers or printing-telegraph machines. The six blank spaces are indicated at i^1 i^2 i^3 i^4 i^5 . When the spacing-key b is depressed, a circuit is closed to the corresponding contact d on the sunflower, and when the rotating arm d' thereof reaches that contact the electromagnet e² is energized to cause the stop e¹ to engage the corresponding tooth of the stop-wheel f and effect a cessation of rotation of the type-wheel, as will be explained, with either of the blank spaces i^1 or i^2 opposite the paper. The manipulation of the key b' will effect the stopping of the type-wheel with either of the blank spaces i^2 i^3 opposite the paper, and the manipulation of the key b² will stop the type-wheel with either of the blank spaces i^4 i^5 opposite the paper.

I have described suitable devices for controlling the operation of the machine; but it will be understood that others may be substituted, if desired. I shall now proceed to describe the machine.

Framework.—In general the machine is provided with a wooden base 19 and a metallic base-plate 20, from which arise the brackets for supporting the various operative parts or mechanisms of the machine and which will be referred to in connection with the parts which they support.

21 indicates the main bracket or standard, which extends upward from the base-plate and in which the carriage and the motor which drives the type-wheel are journaled upon a vertical axis. This bracket is laterally extended near its base to furnish supports and bearings for some of the parts of the machine.

The carriage and type-wheel.—The motor constitutes a part of the carriage on which the type-wheel is rotatively mounted and pivoted, so that it can be impelled to the paper, the paper being arranged vertically and supported by a platen, as will be described.

Referring to Fig. 6, it will be observed that the bracket 21 is provided with two oppositely-projecting studs or pins 22 23, which are arranged in vertical alinement and which operate to rotatively support the carriage, the type-wheel, and its motor.

The motor, which will be described subsequently in detail, is indicated, as a whole, at 24 in Fig. 1 and is provided with sockets for the reception of the pins or studs 22 23. To

the rear end of the motor is attached a forked bracket 25, (see Figs. 1 and 4,) in the lower end of the arms of which is passed a pin 26 for supporting the type-wheel and its carrier. The motor and the bracket 25 constitute a carriage for the type-wheel and its carrier, and they are adapted to be fed with a step-by-step movement about the studs 22 23 from left to right to permit the printing of a line of characters across the sheet of paper and to be returned from right to left with a single continuous movement, the mechanism by which it is accomplished being hereinafter described in detail. The type-wheel 27 is loosely placed upon an upright shaft 28, the upper end of which is journaled in a yoke 29 and its lower end in a step 30, pivoted on and supported by the pin 26. The bifurcated arms constituting the yoke 29 are pivoted at their lower ends on the said pin 26, so that the type-wheel may be moved bodily about the axis of the pin 26 in addition to its movement about the vertical axis of the motor. The shaft 28 and the yoke 29 constitute the carrier for the type-wheel, and they are held away from the paper or sheet to be printed by a spring 31, attached to the yoke and to the bracket 21. On the shaft 28 is placed a bevel-gear 32, which intermeshes with and is driven by a bevel-gear 33 on the shaft 34 of the motor 24. The rotation of this shaft 34 effects the rotation of the shaft 28 and of the type-wheel 27.

The motor.—The motor itself is illustrated in detail in Figs. 12 to 16. It comprises a plurality of permanent magnets 35, arranged radially equidistant about the shaft 34. Each of these magnets is in the form of a bar or strip which is arranged longitudinally with relation to the shaft 34. They are alternately disposed as regards their poles, so that at each end of the motor the north pole or positive end of one magnet is between the south or negative poles of the two adjacent magnets. Within the permanent magnets is arranged a coil 36, wound upon a bobbin 37 and covered with a layer of insulation 38. This coil is connected in series with the pole-changer or transmitter, so that an alternating current is supplied thereto, there being about four thousand alternations or changes of polarity per minute. Secured to the shaft 34 is an armature, (indicated as a whole at 39.) This armature consists of a cylinder having its ends expanded so as to rotate in close proximity to the poles of the permanent magnets 35. Each of the expanded ends 40 is slotted or cut away to provide a plurality of fingers 41. In the form shown there are four permanent magnetic poles at each end of the motor, and there are six fingers on each end of the armature. The armature itself is formed of soft iron, so that it may be magnetized by the coil 36, and it is supported upon the shaft 34 by bushings 42.

The motor-shaft is at one end journaled on a casing or cap 180 at the end of the motor and in bracket 181 at the other end. (See Fig. 1.)

5 Upon the motor-shaft 34 is secured a ratchet-wheel 43, with which a lazy pawl 44 is in engagement for the purpose of preventing a reverse rotation of the armature.

The operation of the motor is as follows: 10 The passage of a current of positive polarity through the coil 36 magnetizes the armature 39, so that one end thereof becomes of positive magnetic polarity and the other of negative polarity. At the positive end of the armature the fingers 41 are attracted by the negative poles of the permanent magnets and are repelled by the positive poles of said magnets. Inasmuch as there are six fingers and four poles, the fingers will be drawn by the 15 magnetic poles of opposite polarity sufficiently to effect a partial rotation of the armature. Upon a change of polarity in the current through the coil 36 the polarity of the armature 39 will be immediately changed, 20 so that the fingers which were previously positive will become negative and will be attracted by the positive permanent magnetic poles, and will be repelled by the negative poles. The permanent magnets being alter- 25 nately oppositely arranged with relation to their polarity, the attractive force upon the armature will be equal at both ends thereof, and for each change of polarity in the operating-current through the coil 36 the armature 39 and the shaft 34 will be advanced one step.

I have stated that there are four permanent magnetic poles at each end of the motor and six fingers on each end of the armature.

It will be understood, however, that I may 40 employ any suitable number of fingers and permanent magnetic poles. In order to assist in the advance movement or step-by-step rotation of the armature, it will be seen that the ends of the permanent magnets are 45 beveled, so that the end surfaces are successively to one side of radii passing from the axis of the shaft 34 through the central longitudinal planes of the permanent magnets.

By reason of the number of fingers and permanent magnets twelve alternations of the current or changes of polarity thereof will effect a complete rotation of the motor, and hence the motor must be geared to the type-wheel accordingly. It happens in the present case that there are twenty contacts on the pole-changer, and hence the motor is geared to the type-wheel shaft at a ratio of twelve to twenty.

Carriage-feeding mechanism.—The mechanism by which the type-wheel carriage is fed will now be described.

It will be seen that secured to the motor is a segmental ratchet 50, which is adapted to be engaged and fed forward step by step 65 by an electromagnetic-ratchet mechanism,

each step or tooth representing one space in a line on the paper. This mechanism comprises an electromagnet, which is indicated at 51, connected in series with the motor. The armature 52 of the magnet is secured to a rock-shaft 53, which is journaled in bearings afforded by lateral extensions of the bracket 21. Secured to the rock-shaft 53 is an arm 54, in the end of which is pivoted a pawl 55, which is adapted to engage the ratchet 50 and feed it one step at a time. This pawl is held in engagement with the ratchet by a helical spring 56, as best shown in Fig. 1. A spring 57 is attached to an arm on the rock-shaft 53 for the purpose of holding the armature 52 normally away from the core of the electromagnetic coils 51, said spring being depended upon for actually effecting the forward movement of the type-wheel carriage, the electromagnet being used for moving the pawl 55 backward to engage a fresh tooth.

After the carriage has been fed step by step across the paper it is returned to its initial starting-point by a continuous movement through the agency of a spring 58, which is coiled about the pin 22, previously referred to, one end of said spring being secured to a pin 59 on the bracket 21 (see Fig. 1) and the other end to the motor. (See Figs. 1 and 2.) It may be here stated that to prevent a reverse movement of the carriage during its step-by-step movement a retaining-pawl 60 extends somewhat beyond the end of the pawl 55, so as to engage a tooth in advance thereof, as best shown in Fig. 2.

Carriage-returning mechanism.—The pawl 60 is provided with a projection 61, which extends under the pawl 55 and which is utilized for raising the pawl 55 to an inoperative position for permitting the return of the carriage to its initial starting-point. The pawl 60 is pivoted upon a support 63, which forms a part of one of the lateral extensions of the brackets 21. (See Figs. 3, 4, and 5.) This pawl is normally held in engagement with the segmental ratchet by a spring 64, attached to the pawl and to the armature 65 of an electromagnet 66, connected in series with the motor and in multiple with the magnet 51. The pawl and the armature are provided with oppositely-projecting fingers. (Indicated at 67, 68, respectively.) These fingers overlap and are engaged, so that when the armature 65 is attracted to the cores of the electromagnet 66 the pawl 60 is moved out of engagement with the segmental ratchet, carrying with it the feeding-pawl 55. To limit the movement of the armature away from the electromagnet, a stop-pin 69 is passed into the support 63 in the path of movement of the said arm 68.

I propose subsequently to explain in detail the circuit relations of the various mechanisms of the machine; but it is necessary at this time, in order to set forth the operation

of the carriage-returning mechanism to state that the return-circuit from the motor is closed through the electromagnet 66 when the carriage has reached a predetermined 5 point in its feed and only when a shift-key on the keyboard is depressed. The devices by which this circuit is closed are hereinafter described in connection with the mechanism for feeding the paper.

10 *Type-wheel-actuating mechanism.*—I have now explained the mechanism for feeding the type-wheel carriage forward step by step and the mechanism for returning the carriage to its initial or starting position, and I shall now 15 explain the mechanism for striking the type-wheel against the paper for effecting the printing of a character upon the paper, and this includes the following devices: Pivoted upon the pin 26, which, as has been stated, 20 is supported in the forked bracket 25, is an arm 70, which is connected by a brace 71 with the yoke 29, so that when the arm 70 is raised the type-wheel carrier is oscillated about its axis and the type-wheel is thrown 25 forward to engage the paper, which is held in proper relation thereto, as I shall hereinafter explain. The armature 52, which, as previously stated, is secured to the shaft 53, is on an arm 72, which projects under the end 30 of the arm 70, as shown in Figs. 1 and 17, so that each time the armature 52 is attracted by the electromagnetic coils 51 the type-wheel carrier is oscillated about its axis to effect the impingement of the type-wheel 35 against the paper. Inasmuch as the attraction of the armature 52 by the magnet simply withdraws the feeding-pawl into the position where it may be carried forward by the spring 57, it will be seen that the passage 40 of a continuous current of electricity through the magnet 51 effects the printing of a character upon the paper, which is followed by the feeding of the carriage when the current ceases.

45 *The platen.*—The paper A is shown as being drawn upwardly from a suitable roll, (not shown,) arranged below the machine, and it is held and supported against a concavo-convex platen, as indicated at 80. In plan view 50 this platen forms the arc of a circle of which the axis of the type-wheel carriage is the center. It consists of an upright metallic shell against which the paper is held by a plurality 55 of fingers (indicated at 81 81 82.) These fingers are resilient, the fingers 81 being supported by a strip 83, attached at its ends to the side edges of the platen, which edges are bent inwardly to form guides for the side edges of the paper strip. The finger 82 is 60 supported by a bracket 84, which serves another function to be described.

65 *Paper-feeding mechanism.*—The paper is fed upward with a step-by-step movement by two coacting disks, wheels, or rolls 85 86, of which the latter is positively driven. The

roll 85 may be shod with hard rubber, and it is loosely journaled in a forked arm 87, journaled in a bracket 88. To the shaft 89, to which the fork 87 is secured, is formed or attached an arm 90, by which the roll 85 may be moved away from the paper. A spring 91 exerts its tension upon the shaft 89 to hold the roll 85 yieldingly against its coacting roll 86 or the paper, which is interposed between them. It will be observed by an inspection of Fig. 1 that the platen is apertured to receive the roll 85. The roll 86 is preferably corrugated or toothed to positively engage the paper and feed it upward by the platen and the type-wheel. This roll is 70 loosely journaled on a stud-shaft 93, which is journaled in standards 94 95, rising from the base 20. Movable with the roll or wheel 86 is a ratchet-wheel 96, these two wheels being secured together by a hub 97, on which they 75 are rigidly mounted. These wheels may be secured "friction tight" on the hub, as shown, or they may be otherwise secured as convenience suggests.

80 On the shaft 93 is a pawl-carrier 98 with a pawl 99 in position to engage the teeth of the ratchet 96. The pawl-carrier is secured upon the end of a sleeve or hub 100, to the other end of which is secured an arm 101, which extends substantially horizontally forward 85 and which carries upon its end a stud 102. A spring 103 encircles the shaft 93, one end being attached to the standard or upright 95 and the other to the arm 101 to move the pawl reversely around the ratchet when permitted. The ratchet is held against reverse rotation by a spring-retaining pawl 104, as shown in Figs. 1, 5, and 6. The stud or projection 102 is normally engaged by a projection 105 on a pivoted latch 106, the end of 90 which extends upwardly into the path of a tripping-stop 107 on the ratchet-segment 50, so that when the carriage has been fed across the paper the stop will engage the end of the latch 106 and move it to the position shown in Fig. 5, so as to release the stud 102 and permit the spring 103 to swing the pawl-carrier to the position shown in Fig. 6, preparatory to feeding the paper upward one step. This action of the spring, however, does not 105 take place immediately upon the release of the stud, but is dependent upon the operation of the carriage-feeding magnet.

110 Rigidly secured upon the shaft 53 is an arm or lever 108, which projects toward the platen and lies above the stud 102, extending past the latch 106. When the type-wheel carriage has nearly reached the limit of its movement across the paper, an electrical impulse, sent through the electromagnet 51 by the manipulation of a space or other key by means to be described, causes the attraction of the armature 52 and the lifting of the arm or lever 108. Inasmuch as at this time the stop 107 has engaged the latch 106 and 115

tripped it, the spring 103 will reversely actuate the pawl-carrier 98 and move it to the position shown in Fig. 6. As soon as the current fails in the electromagnet 51 the spring 57 previously referred to, will return the rock-shaft 53 to initial position, thereby causing the arm 108 to depress the stud 102 on the arm 101, so that it may be again engaged by the projection 105 on the latch 106 as soon as the type-wheel carriage has accomplished a portion of its return movement. It may be stated that the arm 108 oscillates once for each feeding step imparted to the type-wheel carriage; but this can have no effect upon the paper-feeding mechanism, except when the latch 106 has been tripped by the stud 107. To move the latch to and hold it in its locking position, the lower end of the latch is secured upon a shaft 109; about which is coiled a spring 110, the ends of which are attached, respectively, to the shaft and to the base 20, as best illustrated in Fig. 4.

As thus far described it will be seen that when the carriage has reached the limit of its movement across the paper the carriage will be automatically returned upon the depression of a key in the sending apparatus and the paper will be advanced one step. Mechanism is provided by means of which the paper may be fed one or more steps prior to the return of the carriage to its initial or starting point; but inasmuch as this depends upon another feature of the machine I will first explain the operation of the type-shifting mechanism.

Type-shifting mechanism.—I have stated that there are double the number of divisions on the type-wheel that there are keys, so that it is necessary to at times shift the type-wheel on its shaft in order to bring the proper character in printing relation to the paper, and this is accomplished by manipulation of the keys b' b^2 of the keyboard B and mechanism controlled thereby, which I shall describe.

The type-wheel 27 is loose on the shaft and is provided with a hub 120, (see Fig. 7,) having oppositely-extending arms 121 and 122, to which are pivoted fingers 123 124, respectively. The hub 120 has still another arm 125, which is at right angles to those previously described and which has a downwardly-projecting pin 126, the end of which is beveled. Rigidly secured to the shaft 28 is another hub 127 with an arm 128, having two stops 129 and 130, between which the pin 126 may play. The arm 128 has in addition to the stops 129 130 a bevel pin or projection 131, which is adapted to hold the pin 126 between it and either of the stops 129 and 139, so that the type-wheel may be held in either one of two positions relatively to the shaft 28. A spring 132 bears upon the type-wheel and holds the hub thereof yieldingly against the

hub 127, and therefore permits the yielding 65 of the type-wheel and the passage of the pin 126 in one direction or the other past the beveled projection 131. The hub 127 is also provided with another arm 134, having guides 135 for the two fingers 123 124. Affixed to the front of the carriage is the bracket 84, to which reference has been previously made. This bracket is provided with a block or abutment 136 of insulating material near the shaft 28 and in such position that when 75 the type-wheel is stopped in its rotation by the manipulation of either of the two shift-keys one or the other of the fingers 123 124 will engage the block when the type-wheel is swung toward the paper. Hence upon the 80 pressing of a shift-key on the keyboard the type-wheel shaft 28 will be stopped with a blank space opposite the paper, and as the type-wheel is moved toward the paper the end of one of the fingers 123 or 124, as the 85 case may be, will engage the insulated block 136, so that the type-wheel will be shifted one space in one direction or the other relatively to its shaft.

In Figs. 8, 9, 10, and 11 the operation of 90 the type-shifting mechanism is illustrated. In Fig. 8 the type-wheel has been stopped with the finger 124 opposite the block 136; and in Fig. 9 the position of the parts is illustrated after the type-wheel has been moved 95 forward toward the paper to cause the end of the finger 124 to engage the block and shift the type-wheel relatively to its shaft. In Figs. 10 and 11 the position of the parts is illustrated before and after the type-wheel 100 has been shifted in the opposite direction. One of the shift-keys on the keyboard B—as b^2 , for instance—(see Fig. 18,) causes the type-shaft to be stopped in the position shown in Fig. 8, whereas the key b' causes the said 105 shaft to be stopped, as in Fig. 10, with the finger 123 in operative relation to the block 136. Assuming, for instance, that the key b^4 in Fig. 18 is used for the letters "a" and "x" and the letter "a" has been printed 110 and the operator desires to then print the letter "x," he will effect the shifting of the type-wheel upon the carriage by manipulating one or the other of the keys b' b^2 , as the case may be, and then again manipulating 115 the key b^4 to effect the printing of the letter "x." At no time will the shaft 28 be stopped with either of the fingers 123 124 in operative relation to the insulated block 136, except when one or the other of the shift-keys 120 b' b^2 has been manipulated by the operator.

It is necessary that the type-wheel carriage should not be advanced one step when the type-wheel is being merely shifted, and consequently I provide means for rendering inactive the carriage-feeding pawl when either of the shift-keys is depressed. The mechanism by which this is accomplished is illus-

trated in Figs. 1, 2, 3, 6, 9, and 17. Referring particularly to Fig. 6, it will be seen that the carriage-feeding pawl 55 is provided with a tailpiece 140, with which may be engaged an end of an arm 141 on a rock-shaft 142, journaled in suitable bearings. Around the rock-shaft is coiled a spring 143, (see Fig. 3,) which holds the arm 141 normally in inactive position, as shown in Fig. 1 and by the dotted lines in Fig. 6. To the end of the shaft 142 is affixed an arm 144, which forms the armature of an electromagnet 145, arranged vertically on the right-hand side of the machine, as shown in Figs. 2, 4, and 17, and connected in series with the motor and in multiple with the magnets 51 and 66. The movement of the armature away from the electromagnet is limited by a stop-pin 146. When a current is passed through the electromagnet 145, the armature 144 is attracted and the arm 141 is moved to the full-line position in Fig. 6, so as to arrest the subsequent movement of the tailpiece 140 of the feeding-pawl 55, and so render the pawl inoperative with relation to the ratchet-segment 50. It will be recalled that each time any one of the keys of the keyboard is manipulated by the operator the current will flow continuously through the magnet which effects the feeding of the type-wheel carriage and the operation of the type-wheel, and in order that the electromagnet 146 may be energized to move the feeding-pawl to inactive position only when one of the shift-keys is depressed it is arranged in a shunt-circuit k k' . (See Fig. 17.) This circuit includes the bracket 84, which is insulated from the remainder of the machine, the shaft 28 for the type-wheel, a portion of the framework 40 of the machine, which in Fig. 17 is indicated at k' , a movable switch 150, and a contact-plate 151, which is secured upon the bed of the machine, but insulated therefrom. The bracket 84 is provided with a spring-contact 152, with which will be engaged a contact 153 on the arm 134, the said contact 152 being long enough so that it will be engaged by said contact 153 when the type-wheel shaft is in the position shown in Figs. 8 and 10. The contacts 152 and 153 will be engaged only when one of the shift-keys is manipulated by the operator, since the stopping of the type-wheel shaft 28 in any position other than shown in Figs. 8 and 10 will move the contact 153 in such position that upon the movement of the type-wheel to printing position the contacts will not be engaged.

From this description it will be seen that when one of the shift-keys is manipulated by the operator to effect the shifting of the type-wheel on its shaft in the manner described the rock-shaft 142 will be actuated by the attraction of the armature 144 by the electromagnet 145 and the arm 141 will be moved

from the dotted position shown in Fig. 6 to 65 the full-line position, so as to prevent the feeding-pawl from dropping into a fresh tooth of the carriage-ratchet segment 50.

Automatic switch mechanism.—The switch 150, to which reference has been made, is secured upon the shaft 93, which, as will be remembered, supports the paper-feeding wheel 86. By reference to Figs. 2, 4, and 17 it will be seen that the switch 150, which is flexible and which when the shaft 93 is in its normal position rests upon the contact 151, normally completes an electrical connection from the type-wheel shaft 28 to the electromagnet 145.

In this embodiment of the invention it is necessary for the operator when the type-wheel carriage reaches the end of a line to depress a shift-key in order that the carriage may be automatically returned by the returning-spring 58. To this end the electromagnet 66, which when energized effects the lifting of the retaining-pawl 60, as hereinbefore described, is arranged in a branch circuit m in series with the motor and in multiple with the electromagnetic mechanism which effects the feeding of the carriage and the actuation of the type-wheel. By an examination of Fig. 17 it will be seen that the branch circuit m includes a contact-plate 160, arranged adjacent to but insulated from the contact-plate 151, so that it may be engaged by the switch 150 when the shaft 93 is rocked by the spring 103 after the release of the stop or stud 102 by the latch 106.

Assuming that the carriage has reached the end of a line and the stop 107 has engaged the latch 106 and released the stud 102, the passage of a direct current of electricity through the magnet 51 causes the armature 52 to rock the shaft 53 and lift the arm 108. The arm 101 on the shaft 93 will then be rocked by the spring 103 so as to bring the switch 150 against the stationary contact 160, so that current will flow through the branch circuit m when the contact 153 on the type-wheel shaft engages the contact 152 on the bracket 84, which bracket, it will be remembered, is electrically connected with the switch 150. The magnet 66 being thus energized, the retaining-pawl 60 will be lifted, carrying with it the feeding-pawl 55, so that the carriage will be automatically returned by the spring 58 to its starting-point.

It is frequently desirable to feed the paper several steps—as, for instance, to separate one paragraph of printed matter by a large space from the preceding paragraph. This is accomplished when the carriage has reached the end of its line, so as to free the latch 106 from the stud 102 by the manipulation of the space-key. When the parts are all in the position last described, the operator may manipulate the space-key as many times as he desires without printing any character upon

the paper and effect the feeding of the paper, for the depression of the space-key causes a direct current of electricity to flow through the electromagnet 51, which through its armature lifts the arm 108 and releases the arm 101, so that the pawl 9 is moved by the spring 103 for a fresh tooth to feed the paper a step upon the subsequent action of the spring 57. As often as the space-key is depressed by the operator the paper will be fed one step.

The electrical circuits.—I have in some measure described the circuit relations of the parts; but they may be further described, as follows, reference being had to Fig. 17: From the binding-screw 111 a conductor *n* extends to a binding-screw on the side of the motor. In actual practice this conductor, which is suitably insulated, is carried to a cap 170 on the top of the stud 22, as shown in Figs. 1, 2, 3, and 5, and thence to a binding-screw 171 on the motor. From this binding-screw the conductor extends to the coil 36 of the motor, the return-conductor being secured to a binding-screw 172 on the motor. From the binding-screw 172 a conductor *n'* extends to the electromagnet 51 and thence to the binding-screw 112. The branch circuits *k* and *m* are connected in series with the motor, but in multiple with relation to each other and to the electromagnet 51. Except when one of the keys in the keyboard is depressed an alternating current flows through the motor, the periods or alternations, however, being of such short duration as to prevent the attraction of the armature 52 by the electromagnet 51, although they are of sufficient duration to cause the operation of the motor in the manner previously described. When one of the keys is depressed so that the stop-wheel F is held against rotation, a current of one polarity or the other flows continuously through the motor and the electromagnet 51, so as to hold the armature of the motor in the position in which it was stopped and cause the attraction of the armature 52 by the electromagnet 51 and the operations which are consequent thereupon.

It will be understood that the transmitter is connected by branches from a single main circuit to a plurality of machines, so that a single keyboard will control all of the machines, and since but one circuit is employed and said circuit is grounded, as hereinbefore described, the cost of installation of a system embodying my invention will be much less than has been possible with previous page-printing machines, in which at least two distinct circuits from the central station was essential.

I herein refer to that element which carries the printing-types as the type-wheel; but I do not use that term in any limiting sense, for it is evident that so far as certain other features of the invention are con-

cerned any other of the well-known printing mechanisms or type-carriers may be employed as mechanical equivalents thereto.

I have described the motor in detail; but I do not claim it *per se*, as it forms the subject-matter of an application, Serial No. 250,160, filed March 15, 1905. Concerning the motor, it may be stated that since the momentum caused by a change of polarity throws the fingers past the central magnetic lines of force to let the pawl drop back of a tooth in the ratchet the back drag holds the tooth against the pawl, and the pawl therefore indexes or positions the armature and the type-wheel. Since the fingers are past the poles, the next change of polarity causes the fingers to be advanced instead of retarded. The motor controlled as described by the keys or the key-controlled transmitter serves to rotate and selectively position the type-wheel. The motor, the transmitter, and the keys may thus be described as an "electromagnetic selecting mechanism for the type-wheel or the printing mechanism."

Having thus explained the nature of the invention and described a way of constructing and using the same, although without attempting to set forth all of the forms in which it may be made or all of the modes of its use, I declare that what I claim is—

1. In a type-writing machine, a rotary type-wheel, and means for moving said wheel bodily in the arc of a circle about an axis eccentric to and substantially parallel to the axis of rotation of said wheel to bodily feed the wheel to new printing positions.

2. In a type-writing machine, a rotary type-wheel, means for moving said type-wheel about an axis eccentric to and substantially parallel to the axis of the type-wheel, and means for moving said type-wheel radially of said eccentric axis.

3. In a type-writing machine, a rotary type-wheel, means for feeding said type-wheel with an intermittent movement about an axis eccentric to the type-wheel, and means for returning said type-wheel with a continuous motion about said axis.

4. In a type-writing machine, a rotary type-wheel, means for feeding said type-wheel with an intermittent movement about an axis in the arc of a circle eccentric to the type-wheel, and means for moving said type-wheel on an axis transverse to the first-mentioned axis to impart an impression-stroke thereto.

5. In a type-writing machine, a rotary type-wheel, means for rotating said type-wheel to selected positions, and means for automatically thereafter feeding said type-wheel with a step-by-step motion about an axis eccentric to and substantially parallel to the type-wheel.

6. In a type-writing machine, a carriage movable about an axis to feed the type-car-

5. In a type-writing machine, a carriage through an arc, a type-carrier pivotally connected to said carriage on an axis transverse to the first-mentioned axis, and means for moving said type-carrier about its pivot radially relatively to said axis.
10. In a type-writing machine, a carriage movable about an axis to feed the type-carrier through an arc, a frame in which said carriage is journaled, a type-carrier movably connected to said carriage to move in a direction radially of said axis, and means for moving said type-carrier.
15. In a type-writing machine, a carriage movable about an axis to feed the type-wheel through an arc, a frame in which said carriage is journaled, a type-wheel rotatably journaled on said carriage, means for moving said carriage about its axis, and means for moving said type-wheel bodily radially of said axis.
20. In a type-writing machine, a carriage movable about an axis, means for moving said carriage with a step-by-step movement about said axis, a type-wheel journaled on said carriage, and means for rotating said type-wheel to selected positions independently of the movement of the carriage.
25. In a type-writing machine, a carriage movable about an axis, means for moving said carriage with a step-by-step movement about said axis, a type-wheel journaled on said carriage, means for rotating said type-wheel to selected positions independently of the movement of the carriage, and means for moving said type-wheel transversely of its own axis of rotation.
30. In a type-writing machine, a carriage movable about an axis, means for moving said carriage with a step-by-step movement about said axis, a type-wheel journaled on said carriage, means for rotating said type-wheel to selected positions independently of the movement of the carriage, and means for moving said type-wheel transversely of its own axis of rotation.
35. In a type-writing machine, a carriage movable about an axis, means for moving said carriage with a step-by-step movement about said axis, a type-wheel journaled on said carriage, means for rotating said type-wheel to selected positions independently of the movement of the carriage, and means for moving said type-wheel transversely of its own axis of rotation.
40. In a type-writing machine, a carriage movable about an axis, means for moving said carriage with a step-by-step movement about said axis, a type-wheel journaled on said carriage, means for rotating said type-wheel to selected positions independently of the movement of the carriage, and means for moving said type-wheel in lines substantially radial to the said axis of movement of said carriage.
45. In a type-writing machine, a carriage movable about an axis, a frame in which said carriage is journaled to move about an axis, a toothed segment on the carriage, and means on said frame for engaging and moving said toothed segment step by step to feed the carriage and thereby the type-carrier relatively to the paper.
50. In a type-writing machine, a type-carrier, a carriage on which said type-carrier is mounted, a frame in which said carriage is journaled to move about an axis, a toothed segment on the carriage, and means on said frame for engaging and moving said toothed segment step by step to feed the carriage and thereby the type-carrier relatively to the paper.
55. In a type-writing machine, a type-carrier, a carriage on which said type-carrier is mounted to be bodily moved thereby, a frame in which said carriage is journaled to move about an axis, a toothed segment on the carriage, means on said frame for engaging and feeding said toothed segment step by step to feed the carriage, and means for moving said carriage in the opposite direction.
60. In a type-writing machine, a type-carrier, a carriage on which said type-carrier is mounted, a frame in which said carriage is journaled to move about an axis, a toothed segment on the carriage, and means on said frame for engaging and feeding said toothed segment step by step to feed the carriage, and means for moving said carriage in the opposite direction.
65. In a type-writing machine, a type-carrier, a carriage on which said type-carrier is mounted, a frame in which said carriage is journaled to move about an axis, a toothed segment on the carriage, a retaining-pawl engaging said segment, a feeding-pawl and means for disengaging said pawls to permit the return of the carriage.
70. In a type-writing machine, a type-carrier, a carriage on which said type-carrier is mounted, a frame in which said carriage is journaled to move about an axis, means for feeding the carriage, means for returning said carriage, and independent keys for controlling said carriage feeding and returning means.
75. In a type-writing machine, a type-carrier, a carriage on which said type-carrier is mounted, a frame in which said carriage is journaled to move about an axis, means for feeding the carriage, means for returning said carriage, and independent keys for controlling said carriage feeding and returning means.
80. In a type-writing machine, a concave platen, and a type-carrier movable across said platen in a path substantially concentric to said platen.
85. In a type-writing machine, a platen having a concave face, a type-carrier movable across said face, and means for effecting a relative movement of said platen and carrier in a line connecting them.
90. In a type-writing machine, a platen having a concave paper-supporting face, a type-wheel, movable across said face, means for rotating the type-wheel, and means for striking said type-wheel against the face of the platen or the paper thereon.
95. In a type-writing machine, a type-wheel movable about an axis, a platen having a concave face concentric with said axis, means for rotating said type-wheel to a selected position, and means for moving said type-wheel radially of said axis to engage paper on the face of the platen.
100. In a type-writing machine, a type-wheel movable about an axis, a platen having a concave face concentric with said axis, means for rotating said type-wheel to a selected position, and means for moving said type-wheel radially of said axis to engage paper on the face of the platen.
105. In a type-writing machine, a type-wheel movable about an axis, a platen having a concave face concentric with said axis, means for rotating said type-wheel to a selected position, and means for moving said type-wheel in successive radii of said axis to print a line on paper on the face of the platen.
110. In a type-writing machine, a type-wheel movable about an axis, a platen having a concave face concentric with said axis, means for rotating said type-wheel to a selected position about an independent axis to a selected position, means for feeding said type-wheel about said first-mentioned axis across the face of the platen, and means for moving said type-wheel radially of said first-mentioned axis toward the platen.
115. In a type-writing machine, a platen having a concave paper-supporting face, means for maintaining the paper against said face and means for feeding paper longitudinally of said face.
120. In a type-writing machine, a platen having a concave paper-supporting face, means for maintaining the paper against said face and means for feeding paper longitudinally of said face.
125. In a type-writing machine, a platen having a concave paper-supporting face, means for maintaining the paper against said face, means for feeding paper longitudinally of said face, and a key controlling the operation of said paper-feeding means.
130. In a type-writing machine, a type-carrier, a carriage on which said type-carrier is mounted, a frame in which said carriage is journaled to move about an axis, a toothed segment on the carriage, a retaining-pawl engaging said segment, a feeding-pawl and means for disengaging said pawls to permit the return of the carriage.

24. In a type-writing machine, an electric motor, a type-wheel rotated thereby, an electromagnetic mechanism for feeding said motor and type-wheel, and an electric circuit for supplying current to said motor and feeding mechanism.
25. In a type-writing machine, an electric motor, a type-wheel rotated thereby, an electromagnetic mechanism for feeding said motor and type-wheel in series connection with said motor, a key-controlled pole-changer or transmitter and an electric circuit in series connection with said transmitter, and said motor and feeding mechanism.
- 15 26. In a type-writing machine, an electric motor, a type-wheel rotated thereby, an electromagnetic mechanism for feeding said motor and type-wheel, and a key-controlled pole-changer or transmitter in series connection with said motor and said electromagnetic feeding mechanism by a single conductor.
- 20 27. In a type-writing machine, a rotary type-wheel, a motor connected thereto to rotate it, a device for feeding the type-wheel, a device for returning the type-wheel, separate electromagnets controlling said devices, and a single electric circuit including said motor and said magnets for supplying current thereto from the same source.
- 25 28. In a type-writing machine, a rotary type-wheel, a motor connected thereto to rotate it, a paper-feeding device, an electromagnet controlling said device, an electric circuit including said electromagnet and said motor and means whereby said paper-feeding device is operated selectively.
- 30 29. In a type-writing machine, a type-wheel, a motor connected thereto to rotate and selectively position it, means for feeding said type-wheel, an electromagnet for controlling said feeding means, means for effecting the return of the carriage, an electromagnet controlling the last-mentioned means, and an electrical conductor electrically connected with said motor and said electromagnets, whereby current may be supplied thereto from the same source.
- 35 30. In a type-writing machine, a type-wheel, a motor connected thereto to rotate and selectively position it, means for feeding said type-wheel, an electromagnet for controlling said feeding means, means for effecting the return of the carriage, an electromagnet controlling the last-mentioned means, an electric circuit including said motor and said electromagnets with said electromagnets in multiple to each other, and means in said circuit for cutting into and out of said circuit the electromagnet which controls the carriage-returning means.
- 40 31. In a type-writing machine, a type-wheel, a motor connected thereto to rotate and selectively position it, means for feeding said type-wheel, an electromagnet for controlling said feeding means.
- 45 32. In a type-writing machine, a rotary type-wheel, a motor to rotate and selectively position said devices for feeding the carriage, devices for returning the carriage, devices for feeding the paper, electromagnets operating or controlling said devices, and a single circuit including said motor and said electromagnets, whereby current from the same source supplied over a single conductor may be used for energizing them.
- 50 33. In a type-writing machine, a rotary type-wheel, a motor having a rotary armature connected to said type-wheel to rotate and selectively position said type-wheel, separate electromagnetic instrumentalities for feeding, returning and actuating the type-wheel, and for feeding the paper, and a single electric circuit including said motor and said instrumentalities whereby current may be supplied thereto over a single conductor from one source.
- 55 34. In a type-writing machine, a rotary type-wheel, a motor having a rotary armature connected to the type-wheel to rotate and selectively position said type-wheel, separate electromagnetic instrumentalities for feeding, returning and actuating the type-wheel and for feeding the paper, a pole-changer or transmitter in series connection with said motor and said electromagnetic instrumentalities, and a plurality of keys controlling said transmitter including a special key for the type-wheel-returning instrumentalities.
- 60 35. In a type-writing machine, a rotary type-wheel, a motor connected thereto to rotate and selectively position it, means for pivotally supporting said type-wheel and motor to permit them to swing bodily about the same axis which is eccentric to the axis of rotation of said type-wheel, and means for moving said type-wheel about still another axis to impress a character upon the paper.
- 65 36. In a type-writing machine, a rotary type-wheel, an electric motor, gearing connecting the motor and the type-wheel, and means for pivotally supporting said type-wheel and said motor to oscillate about the same axis.
- 70 37. In a type-writing machine, a rotary type-wheel, an electric motor for rotating and selectively positioning said type-wheel, connections between the motor and the type-wheel, means for pivotally supporting said type-wheel and motor on the same axis, and

means for moving said motor and said type-wheel about the said axis to feed the type-wheel relatively to the paper.

38. In a type-writing machine, a carriage, 5 a type-wheel connected to the carriage, a motor connected to said carriage and having a driving member, connections between said driving member and the type-wheel to impart rotation to said type-wheel, a support in 10 which the carriage is pivoted, to oscillate about an axis, and means for moving said carriage about said axis to feed the type-wheel relatively to the paper.

39. In a type-writing machine, a type-wheel, a shaft therefor, a pivotal support for 15 said shaft, a motor having its driving member positively connected to said shaft to rotate and selectively position it, connections between said support and a relatively stationary part of the motor, means for actuating said pivotal support to cause the type-wheel to impinge upon the paper, means for pivoting the motor and the support upon a common axis, and means for moving said 20 motor and said support about said axis.

40. In a type-writing machine, a type-wheel, a shaft therefor, an electric motor having its armature connected to said shaft to rotate and position said type-wheel, a support 25 for the said shaft pivotally connected to a stationary part of the motor, means for pivotally mounting the motor and the support to move about a common axis substantially parallel to said type-wheel shaft, and an electromagnetic mechanism for moving said 30 support about its pivot relatively to the motor.

41. In a type-writing machine, a type-wheel, a shaft therefor, an electric motor 40 having its armature connected to said shaft to rotate and position said type-wheel, a support for the said shaft pivotally connected to a stationary part of the motor, means for pivotally mounting the motor and the support 45 to move about a common axis substantially parallel to said type-wheel shaft, and electromagnetically-controlled instrumentalities for alternately actuating said support and feeding said support and motor 50 about their common axis.

42. In a type-writing machine, a motor mounted to swing bodily about an axis, a platen having a concave face substantially concentric with said axis, a type-wheel, a type-wheel shaft, an oscillatory support for the type-wheel pivotally connected to the motor on an axis transverse to the first-mentioned axis, a power-transmitting connection 55 between the driving member of the motor and the said shaft, and instrumentalities for moving said motor about its axis and for moving said support about said transverse axis.

43. In a type-writing machine, an electric 60 motor mounted to swing about a substan-

tially vertical axis, a platen having a concave face substantially concentric with said axis, a type-wheel, a type-wheel shaft, an oscillatory support for the type-wheel shaft pivotally connected to the motor on a substantially horizontal axis, a power-transmitting connection 70 between the type-wheel shaft and the driving member of the motor, electromagnetic instrumentalities for moving the motor about the vertical axis to feed the type-wheel relatively to the platen and for 75 actuating said support to move the type-wheel toward the platen, and means for supplying current to said motor and to said electromagnetic instrumentalities. 80

44. In a type-writing machine, an electric motor mounted to swing about a substantially vertical axis, a platen having a concave face substantially concentric with said axis, a type-wheel, a type-wheel shaft, an oscillatory support for the type-wheel shaft pivotally connected to the motor on a substantially horizontal axis, a power-transmitting connection 85 between the type-wheel shaft and the driving member of the motor, an electromagnet and its armature, and means actuated or controlled by said armature for moving the motor and the support about the vertical axis and to move the support 90 toward the platen. 95

45. In a type-writing machine, a motor mounted to swing about a substantially vertical axis, a platen having a concave face substantially concentric with said axis, a type-wheel, a type-wheel shaft, an oscillatory support for the type-wheel shaft pivotally connected to the motor on a substantially horizontal axis, a power-transmitting connection 100 between the type-wheel shaft and the driving member of the motor, an electromagnet and its armature, means actuated or controlled by said armature for moving the motor and the support about the vertical axis and to move the support toward the platen, a source of electric current, and electrical conductors connecting said motor and said electromagnet in series with said source. 105

46. In a type-writing machine, a motor mounted to swing about a substantially vertical axis, a platen having a concave face 110 substantially concentric with said axis, a type-wheel, a type-wheel shaft, an oscillatory support for the type-wheel shaft pivotally connected to the motor on a substantially horizontal axis and having an actuating member intersecting the said vertical axis, a power-transmitting connection 115 between said shaft and the driving member of the motor, means mounted on supports stationary with respect to the motor, for effecting the feed of the motor about said vertical axis, and operating said actuating member, said means including a member to engage 120 said actuating member and operatively located with respect thereto. 125

47. In a type-writing machine, a rotary type-wheel, an oscillatory carriage therefor having a ratchet-segment, a feeding-pawl therefor, a retaining-pawl, carriage-returning means, a device for actuating the feeding-pawl, a device for rendering the feeding-pawl and the retaining-pawl inactive, and means whereby the type-wheel controls the operation of the last-mentioned device.
48. In a type-writing machine, a rotary type-wheel, an oscillatory carrier therefor having a ratchet-segment, a feeding-pawl therefor, a retaining-pawl, carriage-returning means, an electromagnet for causing the actuation of the feeding-pawl, an electromagnet for rendering the feeding-pawl and the retaining-pawl active, means for supplying current to said electromagnets, and means controlled by the carriage for controlling the supply of current to the electromagnet by which said pawls are rendered inactive.
49. In a type-writing machine, key-controlled printing mechanism, a key-controlled carriage, and paper-feeding mechanism comprising a paper-feeding device by which the paper is fed at right angles to the printed line, a spring-operated actuator for said device, a latch for rendering said paper-feeding device inactive with the spring under tension, and a stop on the carriage for tripping said latch, whereby said actuator may operate said paper-feeding device.
50. In a type-writing machine, key-controlled printing mechanism, a key-controlled carriage, and paper-feeding mechanism comprising a paper-feeding roll, a ratchet connected thereto, a pawl-carrier having a pawl for engaging and rotating the ratchet, a spring for moving said carrier, a key-controlled device for controlling or actuating the pawl-carrier, a latch for rendering the pawl-carrier inactive with the spring under tension, and a stop on the carrier for tripping said latch.
51. In a type-writing machine, a printing mechanism, a carriage, a carriage-feeding means, a carriage-retaining pawl, a spring connected to the carriage to return it, a switch, means on the carriage for causing the switch to close an electric circuit, a key-controlled circuit, and an electromagnet for moving the retaining-pawl to active position when the circuit is closed therethrough by said switch and the manipulation of a key.
52. In a type-writing machine, a key-controlled make-and-break device; a switch; an electromagnet; an electric circuit including said make-and-break device, said switch and said electromagnet; a movable carriage; carriage-returning means controlled by said electromagnet; and means by which the carriage controls said switch whereby the carriage may be returned when the carriage has reached a predetermined point and the make-and-break device is operated.
53. In a type-writing machine, a movable carriage; a key-controlled make-and-break device; an electromagnet; a switch; an electric circuit including said make-and-break device; said electromagnet and said switch; means by which the carriage causes the automatic closing of the switch when the carriage reaches a predetermined point in its movement; carriage-returning means, and a carriage-retainer adapted to be moved to inactive position by said electromagnet.
- 45 54. In a type-writing machine, a rotary type-wheel having two sets of characters thereon, a shaft on which said type-wheel is journaled, means for rotating and selectively positioning said shaft and said wheel, means for rotatively shifting said wheel relatively to said shaft to bring one or the other of said sets of characters into printing relation, and means for maintaining said wheel in its shift-ed position.
55. In a type-writing machine, a rotary type-wheel having characters thereon, means for selectively positioning said type-wheel comprising a plurality of character-keys less in number than the characters on the type-wheel, means for rotatively shifting said wheel whereby one of said keys may be employed for the printing of two characters, and means for maintaining said type-wheel in its shifted position.
- 35 56. In a type-writing machine, a rotary type-wheel having characters thereon, means for selectively positioning said type-wheel comprising a rotary member and a plurality of character-keys less in number than the said characters on the type-wheel, means whereby said wheel may be shifted the space of one character relatively to said rotary member, to permit some or all of said keys to be used for the printing of each of two characters, and means on said rotary member for maintaining said type-wheel in its shifted position.
- 40 57. In a type-writing machine, a rotary type-wheel having characters thereon, key-controlled means for rotating and selectively positioning said type-wheel, two shift-keys, means by which on the manipulation of either of said keys the type-wheel will be rotatively shifted relatively to said positioning means either in one direction or the other, as the case may be, and means for maintaining said type-wheel in its shifted position after one shift-key has been struck until the other shift-key has been struck.
- 50 58. In a type-writing machine, a rotary type-wheel having characters thereon, key-controlled means for rotating and selectively positioning said type-wheel to bring any alternate one of the characters on the type-wheel into position for printing, and means for rotatively shifting said type-wheel relatively to said positioning means to bring the remainder of said characters into potential

printing relation, whereby any one of the said remaining characters may be positioned for printing by said rotating and positioning means.

5 59. In a type-writing machine, a rotary type-wheel having characters thereon, key-controlled means for rotating and selectively positioning said type-wheel to bring any one of the alternate characters into position for printing, a shift-key, and means controlled thereby for rotatively shifting said type-wheel to bring the remainder of said characters into potential printing relation.

10 60. In a type-writing machine, a rotary type-wheel having characters thereon, key-controlled means for rotating and selectively positioning said type-wheel to bring any one of the alternate characters into position for printing, a shift-key, means controlled thereby for rotatively shifting said type-wheel to bring the remainder of said characters into potential printing relation, a second shift-key, and means controlled thereby for reversely shifting the type-wheel to bring said alternate characters into potential printing relation.

15 61. In a type-writing machine, a rotary type-wheel having printing characters thereon, means for rotatively positioning said type-wheel for printing, means for moving said type-wheel to printing position, means rendered active when the type-wheel is in a predetermined position for printing, to rotatively shift said type-wheel, and means for maintaining said type-wheel in its shifted position.

20 62. In a type-writing machine, a type-wheel having in line, a plurality of characters and six blank spaces substantially as and for the purpose described.

25 63. In a type-writing machine, a type-wheel having in line, a plurality of characters, and six blank spaces in combination with a plurality of character-keys less in number than the characters, a space-key, two shift-keys, and instrumentalities by which the type-wheel is caused to print a predetermined character, or to leave a blank space, or to be rotatively shifted without printing a character.

30 64. In a type-writing machine, a rotary type-wheel, key-controlled means for rotatively positioning said type-wheel and imparting thereto an impression-stroke, means for automatically effecting a relative feeding of said type-wheel and the paper, means for rotatively shifting said type-wheels, and means for automatically rendering said automatic feeding means inactive when the shifting means are actuated.

35 65. In a type-writing machine, a rotary type-wheel, means including a plurality of keys for selectively positioning said type-wheel, means set automatically into operation by the manipulation of said keys for ef-

fecting a relative feed of the paper and the type-wheel, means controlled by one of said keys for shifting the type-wheel, and means for automatically rendering the feeding means inactive when said key is manipulated.

40 66. In a type-writing machine, a rotary type-wheel; means for selectively positioning said wheel comprising a plurality of character-keys and a shift-key and positioning instrumentalities controlled thereby; means controlled by said shift-keys for shifting the type-wheel; and automatic mechanism set in motion by said character-keys and not by said shift-keys for effecting an automatic feed of the type-wheel and the paper, one relatively to the other, when said keys are manipulated.

45 67. In a type-writing machine, a rotary type-wheel; means for selectively positioning said wheel comprising a plurality of character-keys and a shift-key and positioning instrumentalities controlled thereby; means controlled by said shift-keys for shifting the type-wheel; an electromagnet energized by the manipulation of any one of said keys; means in potential relation to said electromagnet for effecting an automatic feed of the type-wheel and the paper, one relatively to the other; and means for preventing the operation of said feeding means by said magnet when said shift-key is manipulated.

50 68. In a type-writing machine, a rotary type-wheel; means for selectively positioning said wheel comprising a plurality of character-keys and a shift-key, and instrumentalities controlled thereby; means controlled by said shift-keys for shifting the type-wheel; an electromagnet energized by the manipulation of any one of said keys, means in potential relation to said electromagnet for effecting an automatic feed of the type-wheel and the paper, one relatively to the other; and an electromagnet and mechanism operated thereby for rendering said feeding means ineffective when the shift-key is manipulated.

55 69. In a type-writing machine, a rotary type-wheel; means for selectively positioning said wheel comprising a plurality of character-keys and a shift-key, and instrumentalities controlled thereby; means controlled by said shift-keys for shifting the type-wheel; an electromagnet energized by the manipulation of any one of said keys, means in potential relation to said electromagnet for effecting an automatic feed of the type-wheel and the paper, one relatively to the other, an electromagnet and mechanism operated thereby for rendering said feeding means ineffective when the shift-key is manipulated, electrical connections for connecting said electromagnets in multiple, and a make-and-break device controlled by the shift-key for cutting the second magnet into and out of circuit.

60 70. In a type-writing machine, the combination of

nation of the following instrumentalities, to wit, a rotary type-wheel; an electric motor for rotating and selectively positioning said type-wheel; key-controlled electromagnetic mechanisms for effecting a relative feed of the paper and the type-wheel, for imparting an impression-stroke to the type-wheel, for shifting the type-wheel; a plurality of keys including a shift-key; and electrical connections for connecting said electromagnetic mechanisms and said motor in a circuit.

71. In a type-writing machine, the combination of the following instrumentalities, to wit, a rotary type-wheel; an electric motor for rotating and selectively positioning said type-wheel; key-controlled electromagnetic mechanisms for effecting a relative feed of the paper and the type-wheel, for imparting an impression-stroke to the type-wheel, for shifting the type-wheel; a plurality of keys including a shift-key; electrical connections for connecting said electromagnetic mechanism and said motor in a circuit; and means by which upon the manipulation of the shift-key and the operation of the shifting mechanism the said feeding mechanism is rendered inactive.

72. In a type-writing machine, a type-wheel, a supporting member therefor, means for imparting an impression-stroke to the type-wheel, means for selectively positioning said type-wheel, an abutment, and means connected to the type-wheel and adapted to engage said abutment to effect a rotative shifting of the wheel the space of one character, when said type-wheel makes its impression-stroke.

73. In a type-writing machine, a type-wheel, a supporting member therefor, means for imparting an impression-stroke to the type-wheel, an abutment, and means connected to the type-wheel and positioned

thereby with respect to the abutment, so as to engage said abutment and shift the wheel in one direction or the other the space of one character, when said wheel makes its impression-stroke.

74. In a type-writing machine, a type-wheel, a supporting member therefor, means for imparting an impression-stroke to the type-wheel, an abutment, and fingers on the type-wheel for alternately engaging the abutment to shift the type-wheel in one direction or the other the space of a character.

75. In a type-writing machine, a rotary type-wheel having a line of characters and blank spaces, a supporting member about which it may be shifted one step in either direction, an abutment located adjacent the path of the type-wheel when it makes an impression-stroke, and means connected to and positioned by the type-wheel for engaging said abutment to effect a shifting of the type-wheel when the type-wheel is positioned with a blank space opposite the paper.

76. In a type-writing machine, printing mechanism arranged to print certain characters, shifting mechanism for causing said printing mechanism to print other characters, means for effecting a relative feed of the paper and the printing mechanism, means for effecting the return of the carriage, a shift-key controlling the shifting mechanism, keys controlling the printing mechanism, and means by which the shift-key renders the carriage-returning means active when the carriage is fed to a predetermined position.

In testimony whereof I have affixed my signature in presence of two witnesses.

ANDREW T. MACCOY.
